UNITED STATES PATENT OFFICE.

HIRAM RICHARD, OF HOOPER, COLORADO.

PRESS.

No. 903,003.

Specification of Letters Patent.

Patented Nov. 3, 1908.

Application filed November 5, 1907. Serial No. 400,804.

To all whom it may concern:

Be it known that I, HIRAM RICHARD, a citizen of the United States, residing at Hooper, in the county of Costilla and State of Colorado, have invented new and useful Improvements in Presses, of which the following is a specification.

The invention relates to an improvement in presses, being particularly directed to a baling press and comprehending an improvement in the feeding mechanism and in the power mechanism for such presses.

The main object of the present invention is the provision of a power mechanism for baling presses in which a continuous even power for operating the press is supplied from the movement of the draft animals.

Another object of the present invention is the provision of feeding mechanism for the press, the parts being constructed and arranged for automatic operation so that the movement of the main or pressure piston under the influence of the power means will automatically feed the material into proper position for the action of the piston.

The invention will be described in the following specification, reference being had particularly to the accompanying drawings, in which:—

Figure 1 is a plan view of my improved press. Fig. 2 is a side elevation of the same. Fig. 3 is an enlarged side elevation partly in section of the pressing apparatus. Fig. 4 is an enlarged plan of the power apparatus, the draft tongues being omitted. Fig. 5 is a sectional view partly in elevation illustrating the support for the turn-table. Fig. 6 is a plan of the bearing ring of the power apparatus. Fig. 7 is a side elevation of the same. Fig. 8 is a plan of the feed chute. Fig. 9 is an elevation of the head board. Fig. 10 is a front view of the operating lever for releasing the head board mechanism.

Referring particularly to Figs. 1, 2, and 3 of the drawing my improved press comprises an inclosed rectangular box-like member 1 provided with a skeleton rectangular extension 2 as is usual in presses of this character. Slidably mounted within the inclosed portion 1 of the press is a piston 3, to which is connected a stem 4 designed to be operated by the power mechanism to be presently described.

The relatively upper portion or wall of the press is formed with a feed opening 5 in

which is pivotally mounted a feed chute 6. The chute 6 comprises a platform 7 pivotally supported adjacent the forward edge of the opening 5, that portion of the platform in advance of the opening having flaring side walls 8, while that portion of the platform overlying the opening being without the side walls. Overlying the opening 5 is a guide housing 9, comprising side walls 10 and an upper or top wall 11, the latter inclining upwardly from the relatively rear edge of the opening and being provided at its relatively forward edge with a roller 12. A feeding member 13 is mounted in the feed chute 6, said member comprising an end plate 14 of a size to fit between the flaring walls of the chute and an arm connecting the plate 14 with the upper forks 15 of an operating lever 16, the platform 7 being longitudinally recessed at 17 to permit the passage therethrough of the upper forks of the lever. Below the platform 7 the lever is pivotally supported at 18 from the forward wall of the casing 1, said lever extending into the path of the stem 4 of the piston 3. The piston 3 is provided with a forward projection 19, adapted in the movement of the piston in one direction to engage the lower end of the lever 16 and move the feed member longitudinally of the feed chute, the reverse movements of the piston 4 actuating the lever in the opposite direction through the medium of a pin 20 carried by the stem and designed to engage the lever.

The relatively rear ends of the side walls of the casing 1 are formed on their inner surfaces with aligned right angled slots or ways 21, the lower portion of which extends longitudinally of the casing 1, while the forward or vertical portion communicates with a slot 22 formed in the upper wall of the casing. This slot is designed to permit the admission of the head boards 23 for the bales, the slot being of a length and width to permit the entrance of said boards, while the ways 21 are designed to receive pins 24 projecting from the side edges of the board and guiding the board during movement in the casing 1. A holding device 25 is applied to each side of the casing 1, comprising spaced connected arms 26 pivotally mounted at 27 on the outer surface of one of the side walls of the casing, the forward ends of said arms being projected laterally to extend within the casing 1 and form stops against

which the board 23 is held in the initial operation of the press. The holding member is maintained in normal or operative position through the medium of a leaf spring 5 28, designed to overlie and bear upon the cross bar 29 connecting the arms.

In connection with the head boards I contemplate the use of a device for the automatic delivery of said boards in proper position and at proper intervals in the operation 10 of the press. This automatic apparatus includes a bolt 30 designed to normally overlie the slot 22 and held in such position through the medium of a coiled spring 31. In advance 15 of the slot 22 the upper wall of the casing 1 is provided with a standard 32 and to the upper end of the standard is secured a spring pressed dog 33, the position of the dog with relation to the bolt 30 is such that when 20 the head board is resting upon said bolt, the upper edge of said board will be engaged by the dog and retained in position to drop through the slot.

At the remote or delivery end of the press 25 I arrange a lever 34 provided at an appropriate point on its inner surface with a projection 35, the lower end of the lever being pivoted to the press proper and the upper end connected by a wire or other flexible 30 connector 36 with the bolt 30. As the bales with their respective head boards are fed longitudinally of the press, the head board in advance will engage the projections 35 of the lever 34 rocking the same on its pivot 35 and withdrawing the bolt 30 from beneath the head board held between said bolt and the dog 33. The board so held is thus free to drop through the slot 22 in position to form the head board for the next bale. 40 With the head board supplied as desired it is obvious that by this construction they will be continuously and automatically delivered in proper position in the press, the ways 21 guiding the boards during the formation of 45 the bale and the stops of the holding member serving to limit movement of the boards during the pressing operation.

In connection with the press described I have devised a novel form of power apparatus by which the piston 3 may be continuously and properly operated. This apparatus, which is more particularly illustrated in Figs. 1 and 4, comprises a skeleton base frame 36' on which is secured an annular member or ring, hereinafter termed the operating ring. The skeleton frame is extended beyond the base of the power apparatus to provide a housing 37' for the forward end of the piston stem 4, and connected to the forward end of said piston and to the frame 36', preferably centrally of the latter are toggles 38. Centrally of the skeleton frame is fixed a bearing stud 39 on which is rotatably mounted a casting 40 carrying at the upper end a plate 41 to which

are secured cross arms 42. The stud 39 is preferably of frusto-conical form, the casting, of course, being shaped to accurately fit the stud. The cross arms 42 are arranged at right angles, and are so disposed with relation to the operating ring 37 that in the movement of said cross arms on the pivotal support provided by the stud 39 said arms will bear upon the upper surface of the ring. The respective ends of the toggles resting 70 upon the upper surface of the ring 37 are arranged to be engaged by the cross arms 42. At appropriate points in the ring 37, that is at a point underlying one of the toggles when the latter is in fully open position, as at 43 75 and at a second point underlying the other toggle when the same is in fully closed position, as at 44, the operating ring is formed with a depression which is of a size to receive the respective toggles and permit the 80 same to fall below the upper surface of the ring, as clearly shown in Fig. 7. Secured to the cross arms 42 are sweeps 45 which project at right angles with respect to each other so that four such sweeps are arranged at 85 equidistances apart and extending beyond the cross arms, the ends of the sweeps carrying the usual swingletrees 46 or other means for the attachment thereto of draft animals.

In the operation of the power apparatus 90 it will be evident that in the rotation of the cross arms one of the toggles, assuming them in fully open position, will be engaged by the particular cross arm and said toggles will be forced into closed position, as will be obvious, thus moving the piston 3 toward pressing position. The closing movement of the toggles will continue until the particular toggle engaged rides into depression 44, when 95 said toggle drops below the plane of the operating ring and, therefore, out of the path 100 of the particular cross arm. In this position the toggles are fully closed one of them being in the depression 44 and the other disposed just beyond said depression, as shown 105 in Fig. 4. The cross arm operating to close the toggles as described will now ride over the toggle initially engaged and engage the next toggle, thus in continued movement 110 forcing the toggles open, such movement being continued until the toggle now engaged rides into its depression 43, as shown in Fig. 1, thus permitting the particular cross arm to ride over the toggle last operated. The 115 toggles are thus opened and closed by each 120 cross arm, it being understood that as one cross arm frees itself or is freed from the toggle operated thereby to open the toggles, the next successive cross arm is in position to pick up the initially operated toggle to 125 again close the toggle. The movement is thus continued during the operation of the power apparatus, each closing and opening of the toggles serving to insure a complete reciprocation of the stem 4 and, therefore, 130

operation of the pressure piston. As the stem moves forward under the opening movement of the power apparatus the projection 19 engages and rocks the lever 16. This 5 movement forces the feed member 13 longitudinally of the platform 7, such movement being continued until said member rides into engagement with the roller 12 of the housing, the further movement of said feed member 10 tending to depress the rear or free end of the feed chute and deliver the material thereon into a position to be acted upon by the piston 3. The return movement of the parts 15 serves to return the feed chute to normal position, again closing the opening 5 and adapting the chute for the reception of a fresh charge. The operation is thus practically automatic, the novel form of power apparatus insuring a steady and continuous 20 operation of the pressure piston, while the movement of said piston serves to automatically feed the material at the proper time and in the proper quantity and also to provide the automatic delivery of the head 25 boards for the bales.

Having thus described the invention what is claimed as new, is:—

1. A baling press formed with a feed opening, a feed chute normally closing said 30 opening, and means operated in the movement of the plunger to actuate the feed chute to uncover the opening and simultaneously deliver the material from said chute through the opening.

35 2. A baling press formed with a feed opening, a feed chute normally closing said opening, a feed member mounted in the chute, means actuated by the piston for operating said feed member, and means carried 40 by the press for causing the feed member in operation to tilt the feed chute into delivery position.

45 3. The combination with a baling press and a piston therefor, of a power apparatus for said piston including a plurality of independent toggles connected to the piston, an operating ring for supporting said toggles, said ring being formed with depressions to receive the toggles, and means for engaging 50 said toggles in succession and operating them respectively in opposite directions.

55 4. The combination with a baling press and a piston therefor, of a power apparatus for said piston including a plurality of independent toggles connected to the piston, an operating ring with which said toggles are

arranged in contact, said ring being formed with a plurality of depressions corresponding respectively with the closed position of one toggle and the open position of the other, and cross bars adapted in operation to successively engage the respective toggles and force them into registry with the ring depressions.

5. A baling press formed with a feed 65 opening, a feed chute normally closing said opening, and means operative in the feeding of the material for actuating the feed chute to uncover the opening.

6. A baling press formed with a feed 70 opening, and a movable feed chute normally closing said opening.

7. A baling press formed with a feed 75 opening, and a pivotally supported chute normally closing the opening.

8. A baling press formed with a feed opening, a feed chute normally closing the opening, a feeding means for forcing the material longitudinally on the chute, and means carried by the press to engage the 80 feeding means and cause the same to tilt the feed chute to uncover the feed opening.

9. A power apparatus for baling presses including a plurality of independent toggles connected to the piston of the press, means 85 for normally supporting the toggles, and means for successively engaging the toggles, said supporting means being formed to permit the toggles to move out of the plane of the influence of the engaging means in certain 90 positions of the toggles.

10. A power apparatus for baling presses including a piston, comprising a plurality of independent toggles connected to the piston, means for engaging the respective toggles in succession to reciprocate the piston, and means for limiting the influence of the 95 engaging means upon the toggles.

11. The combination with a baling press and a piston therefor, of a power apparatus 100 including a plurality of independent toggles, means for engaging the respective toggles in succession to reciprocate the piston, and means to permit independent movement of the toggles to dispose them beyond influence 105 of the engaging means.

In testimony whereof I affix my signature in presence of two witnesses.
